(57) **CLAIM**

The ornamental design for a touch panel, as shown and described.

DESCRIPTION

FIG. 1 is a front, right and bottom perspective view of a touch panel, showing my new design;
FIG. 2 is a rear, right and bottom perspective view thereof;
FIG. 3 is a top view thereof;
FIG. 4 is a bottom view thereof;
FIG. 5 is a left side view thereof;
FIG. 6 is a right side view thereof;
FIG. 7 is a front view thereof;
FIG. 8 is a rear view thereof; and,
FIG. 9 is a front and bottom perspective view thereof.
The broken lines in the drawings depict portions of the touch panel that form no part of the claimed design.

1 Claim, 9 Drawing Sheets
